CARD HOLDER

Max E. Redmond, Minneapolis, Minn.

Application April 9, 1937, Serial No. 135,950

2 Claims. (Cl. 40—16)

This invention relates to removable towel racks suitable for selectively mounting at any desired position without interfering in any manner with the attaching surface.

5 The principal object of the present invention is the provision of a removable towel rack, having a pocket integral therewith for the reception of an indicia-bearing member, whereby the indicia thereon is exposed to view.

10 Another object of this invention is the provision of a towel rack attachable to the wall by means of vacuum cups, and having wall rests, spaced apart from the suction cups, adjustable to and from the wall wherein the rack is secured.

15 Other objects of the invention are simplicity and economy of construction, ease and security of attachment and adaptability for attachment to surfaces of different forms.

20 Minor objects will appear during the course of the specification, wherein reference will be had to the drawing, in which:

Figure 1 is a perspective view of a towel rack in the operative position on a wall, embodying this invention.

25 Fig. 2 is an enlarged, foreshortened, elevational view of the towel rack.

Fig. 3 is a sectional view, showing the bracket in elevation.

Fig. 4 is a sectional view, taken on line IV—IV 30 of Fig. 2.

Fig. 5 is a view similar to that shown in Fig. 3, with the towel rack positioned on a planar wall, and,

Fig. 6 is a modified form of the bracket, where- 35 in the pocket is open at the top.

Throughout the several views, like reference characters refer to similar parts, and the numeral 10 designates a towel bar of any suitable cross elevational area adapted to serve as a sup-

40 port for towels or similar articles. A bracket 12 is provided at opposite ends of said bar and is provided with recesses 14, into which the end portions of the bar 10 are respectively inserted.

The main body of bracket 12 is provided at 45 its inner portion with a saucer-shaped member 16, in which is mounted a suction cup 18. This suction cup is provided with a screw-threaded projection 20, by means of which it is attached to the bracket, as clearly shown in Fig. 4. It will be noted that the outer periphery of member 16 will substantially contact suction cup 18 when the same is in the operative position, thereby preventing undue wobbling of the bracket.

Extending downwardly intermediate the ends 50 of bracket 12, is an arm 22, which terminates at

a point removed from the suction cup and is provided with an adjustable rest 24, slidably mounted in recess 26 formed in 22. A screw-threaded bolt 28, molded in rest 24, serves to hold said rest in any desired position relative to arm 22.

5 It will be noted by referring to Figs. 3 and 4 that when the wall W is offset, the rest 24 is necessarily extended to maintain the body portion of bracket 12 in perpendicular relation to the wall. One of the main advantages of this structure is that, due to the contacting of the wall by rest 24, the pull on the suction cup will be substantially at right angles to the plane of the wall, thereby precluding the possibility of tipping the vacuum cup by applying pressure only to the 10 central portion thereof.

The lower end of arm 22 is provided with a hook member 30, on which may be supported a wash cloth or any other article. The front portion of bracket 12 is provided with an open pocket 20 32, which is adapted to receive an indicia-bearing member or card 34, with the indicia 36 thereon exposed to view. It will be noted that this pocket is formed by producing an undercut 38 in the bracket, with one end 40 open for the reception 25 of a planar indicia member. The exact shape or position of this pocket is not so material.

Referring to the modified form as shown in Fig. 6, it will be observed that the opening 42 to the pocket is positioned at the top side so that the indicia member may be simply dropped to position. Since one of the principal objects of this invention is the provision of means whereby particular towel racks may be designated for use by certain guests or persons, it is contemplated that 30 35 an indicia member shall be used which will allow for the changing of the name thereon. It will be noted that each of the end brackets is provided with a pocket so that in case it is desired to place the towels of two guests on the same rod, 40 a division member 44 may be utilized.

From the foregoing description it is evident that I have produced a simple and efficient towel rack which may be readily positioned at any desired point on the bath room wall, without the 45 use of any outside fastening means. Furthermore, the same may be removed, dismantled and stored in a very small space. This towel rack is intended primarily for guest service, but may be used for additional temporary towel rack requirements whenever any such need may be present.

50 What I claim is:

1. In a bracket having a body portion and a transversely disposed outer head extending beyond each side of said body portion, and trans-

verse bearing opening formed transversely through said body portion adjacent said head; a depression formed in the outer face of said head, said depression being undercut at its base along opposite edges, and being open at one end to receive an indicia bearing plate with opposite edges thereof extending into said undercut whereby the plate is secured in the operative position; and adjustable means associated with said bracket whereby the angular relation of the plate relative to the supporting wall is varied.

2. In a bracket comprising a body portion a

transversely disposed outer head extending beyond each side of said body portion; a depression formed in the outer face of said head, said depression being undercut at its opposite sides and one end, and being open at its other end to receive an indicia plate with three edges thereof extending into said undercut with the indicia exposed to view; and means associated with said bracket and adjustable to vary the surface angle of the indicia plate contained in said depression toward or from the vertical.

MAX E. REDMOND.
